MACHINE FOR TREATING SKINS AND
THE LIKE

Bernard C. Nelson, Norwood, Mass.

Original application July 18, 1942, Serial No.
451,461. Divided and this application April 4,
1945, Serial No. 586,515

4 Claims. (Cl. 69—27)

1

This invention relates to machines for treating skins, and particularly to drums used for same.

Broadly, it is an object of my invention to provide a drum for fur treating machines for treating skins to produce smoother and better skins while giving the hair of the skin a better lustre.

This application is a division of my co-pending application, Serial No. 451,461 which issued as U. S. Patent No. 2,376,500, granted May 22, 1945.

A further object of my invention is to provide a drum for treating skins which has a series of grooves so arranged upon the face of the drum which will cause the heat to be distributed more evenly upon the hairs of the skin to prevent such hairs from being singed.

A further object of my invention is to provide a plurality of substantially V-shaped grooves in combination with additional circumferential grooves and parallel straight grooves, the aforesaid grooves being of different depth, so that the skins being treated beneath the face of the drum will obtain a better finish.

For a fuller understanding of the nature and objects of my invention, reference is had to the following detailed description in connection with the accompanying drawing in which:

Fig. 1 is a side elevation of a skin treating machine showing the drum in relation to the rest of the machine.

Fig. 2 is a view of a fragmentary portion of the cylindrical surface of the drum developed into a plane.

Fig. 3 is a section taken through line 3—3 of Fig. 2.

Fig. 4 is a view of a fragmentary portion of the cylindrical surface of a modification of the drum shown in Fig. 2 developed into a plane.

Fig. 5 is a vertical section taken through a central portion of the drum shown in Fig. 1.

Referring to the drawing, numeral 10 indicated a machine for treating skins and the like, comprising a frame 11 having a table 12 in which a blanket 13 is mounted, movable vertically.

An ironing drum 14, having a hollow shaft 15 is rotatably mounted in bearings 16 upon the table 12. The ironing drum 14 is provided with a central pipe 55 in which there is a series of holes 56 for gas for heating the interior of the drum 14. Through the central portion of the drum there is a shaft 15 also having a series of holes 58 which permits the heat to enter the interior of the drum, since the drum is made of metal the heat is readily transmitted to the

2

circumferential surface of the drum. Instead of gas, it is a simple matter to replace gas heat with electricity and use thermostatic means for automatically controlling the heat.

5 The frame 11 comprises a pair of parallel side walls 17 which have low front portions 18 and high rear portions 19. A pair of parallel bridge members 20 are mounted across the low portions 18 and are connected to the side walls 17 in unitary relation. The bridge members 20 have inclined sides extending upwardly from the outer faces of the side walls 17 terminating in brackets on which the table 12 has been fixed.

The rear portion of the table 12 is formed 15 with a large rectangular opening in which the blanket 13 is mounted. A bar 22 extends across the rear of the rectangular opening, bar 23 extends across the front of the central part of the table 12 with bar 24 slightly higher than bar 23 and placed between bars 22 and 23, all the bars being parallel to one another. The blanket 13 is rotatably mounted on bars 22, 23, and 24.

The rear portion of blanket 13 is sloped downwardly toward the rear of the machine. The 25 blanket 13 may be made of a sheet of felt material as shown, or of a suitable cloth which may be reinforced and supported by a wire mesh belt 26 of the same width as the blanket 13 so that it assists in tautly supporting the blanket 13. The means for lifting and lowering the blanket 13 comprise a link which is pivotally connected by a pin 28 to a bracket. The link 27 extends downward and rearward and pivotally connects with a lever 30. The front end of the lever 30 terminated in a pedal 31 by means of which the front end of the lever may be depressed.

Lever 39 is pivotally supported intermediate its ends on a pin 32 in lugs 33 extending from a bracket which is secured to the side walls 17 of the frame 11. A spring 35 is connected between the bottom end of the link 27 and a stationary rod 36 of the frame and serves to maintain the blanket 13 in its lower position. When the pedal 31 is depressed, the blanket will move upwardly 40 into engagement with the drum 14. As shown in Fig. 1, the bearings 16 are secured to the overhanging portions 19 of the frame 11. The outer end of the hollow shaft 15 carries a pair of pulleys for contact with a belt, one pulley being keyed to the hollow shaft 15, and the other pulley being freely rotatably mounted on the hollow shaft. The hollow shaft as afore described may 45 contain gas and the small openings serving as gas jets for heating the interior of the roller as

shown in Fig. 5. Any well known belt shaft mechanism may be used for shifting the belt from one pulley to the other. The ironing drum may be covered with a dust and heat shield and also to prevent excessive heat, if any, from reaching the skins placed upon the blanket 13.

As shown in Figs. 2 and 3, the drum 14 has a plurality of substantially V-shaped grooves 43, the apices being positioned in offset relation with the middle of the drum so as to cover the entire circumference of the drum with the grooves. As shown in Fig. 3, the grooves 43 are of triangular cross section, each groove having a radially positioned wall 44 and a wall 45 positioned at an acute angle to the radial wall 44. The surface of the drum 14 has, in addition to the V-shaped grooves 43, a series of parallel uniformly spaced circumferential grooves 46 and a series of parallel longitudinal grooves 47, spaced apart the same distance as the circumferential grooves, thus creating a series of squares 34. During rotation of the drum 14, these grooves serve to circulate the heated air with the outer air within the grooves and cause the hairs of the skin to raise and stretch while an evenly distributed heat is applied to the skin.

Referring to Fig. 4, numeral 48 represents another modified drum very much like the drum shown in Fig. 2, except that the longitudinal grooves 49 are uniformly spaced apart a lesser distance within the circumferential grooves 50; the large V-shaped grooves 51 being similar to the V-shaped grooves 43 of Figs. 2 and 3. As shown in Figs. 2 and 3, the grooves 46 and 47 are cut with straight walls so that in section they appear rectangular as seen in Fig. 3, however, these grooves may be made V-shaped instead of being cut vertically, if so desired.

I have found that drums constructed like those shown in Figs. 2 and 4 will stand exceptionally long wear, thus permitting the drum to remain in constant use so that production will not cease for necessary repairs. It should be understood that the different drums listed in the drawing and described in the specification may be designed for application upon all of the well known machines for treating skins of different animals.

It is obvious that various changes and modifications may be made in the details of construction without departing from the general spirit of the invention as set forth in the appended claims.

I claim:

1. A skin treating machine comprising a circular drum, heating means within said drum, said drum having a plurality of substantially V-shaped grooves, the junction point of which is positioned on either side of the circumferential medial line of said drum, a series of parallel straight circumferential grooves crossed by a series of parallel straight grooves in said drum, said grooves being less in depth than said V-shaped grooves, said straight and V-shaped grooves being uniformly spaced around the entire drum.

2. A skin treating machine comprising a circular drum, heating means within said drum, said drum having a plurality of substantially V-shaped grooves, the junction point of each is positioned on either side of the circumferential medial line of said drum, a series of parallel straight circumferential grooves crossed by a series of parallel straight grooves in said drum, said parallel grooves being spaced apart a lesser distance than said circumferential grooves creating rectangles, said straight and V-shaped grooves being uniformly spaced around the entire drum.

3. A skin treating machine comprising a circular drum, heating means within said drum, said drum having a plurality of substantially V-shaped grooves, the junction point of which is positioned on either side of the circumferential medial line of said drum, a series of parallel straight circumferential grooves crossed by a series of parallel straight grooves in said drum, said grooves having sloping walls and being less in depth than said V-shaped grooves, said straight and V-shaped grooves being uniformly spaced around the entire drum.

4. A skin treating machine comprising a circular drum, heating means within said drum, said drum having a plurality of substantially V-shaped grooves, the junction point of which is positioned on either side of the circumferential medial line of said drum, a series of parallel straight circumferential grooves crossed by a series of parallel straight grooves in said drum, said parallel grooves having sloping walls spaced apart a lesser distance than said circumferential grooves creating rectangles, said straight and V-shaped grooves being uniformly spaced around the entire drum.

BERNARD C. NELSON.
